UNITED STATES PATENT OFFICE.

EDWARD F. BARTON, OF RAVENNA, OHIO, ASSIGNOR OF ONE-HALF TO
THEODORE GRUNDEL, OF SAME PLACE.

NAILING-MACHINE.

SPECIFICATION forming part of Letters Patent No. 295,515, dated March 25, 1884.

Application filed December 5, 1883. (No model.)

To all whom it may concern:

Be it known that I, EDWARD F. BARTON, a citizen of the United States, residing at Ravenna, in the county of Portage and State of Ohio, have invented a new and useful Improvement in Nailing-Machines, of which the following is a specification.

In the drawings forming a part of this specification, Figure 1 is a plan. Fig. 2 is a side elevation. Fig. 3 is a vertical section at the line *y* in Fig. 1. Fig. 4 is a vertical cross-section at the line *x* in Fig. 1, and Fig. 5 is a similar section with carrier *a* turned forward in position to receive a nail.

Carrier *a* is of a thickness to receive but one nail at a time in its slot *a'*. It is turned on its axis a quarter of a revolution to receive a nail in a perpendicular position from the inclined slotted trough or conductor *b* and discharge it in a horizontal position in the trough *c*. Carrier *a* is pivoted to the upright part of conductor *b*. To the side of carrier *a* is attached spring *e*, having its side edge even with the outer end of slot *a'* for the head of the nail to rest on. When carrier *a* is turning to deliver a nail in trough *c*, and its slot *a'* is in nearly a horizontal position, the inner side of spring *e* comes in contact with the side of trough *c*, which presses the spring away from the side of carrier *a* and permits the nail to fall from the slot into trough *c*. The lower side of slot *a'* next to spring *e* is beveled to allow the nail to fall. A thin piece of steel, *c'*, is attached to the side of trough *c*, to press out spring *e* and prevent wearing away the side of the trough. Carrier *a* is turned by means of rod *d*, driver *n*, levers *b' b' b'*, cord *l*, and treadle *t*. Rod *d* is connected with carrier *a* at one end, and with an upward-projecting lug, *i*, on driver *n* at the other end. Lug *i* slides loosely on rod *d* between nut *n'* on the screw-threaded end of the rod and collar *m*, which is adjustable on the rod by a set-screw, to determine the extent of movement of carrier *a*. Driver *n* is a rod connected with lever *b'* by a pitman, *n'*. It slides in trough *c*, whose rear end is formed to hold and guide the driver in the trough. Trough *c* is formed with a lateral projection or lug, *c'*, which is slotted to be adjustably held by a screw to

the upright part of conductor *b*. Trough *c* is also held from moving endwise by being formed on its lower side to fit in groove *g* in the upper side of frame *f* at right angles to the trough. Conductor *b* is firmly bolted through its horizontal part or foot in groove *g*.

In the drawings the machine is shown with two carriers and the mechanism described for operating them in order to drive two nails at once. One of the conductors *b*, with its carrier *a*, trough *c*, rod *d*, driver *n*, and pitman *n'*, is adjustable at different distances from the other driver by being bolted to frame *f* through a slot, *g'*. In making the adjustment its pitman *n'* slides on rod *e'*, connected with levers *b' b'*. Each of the pitmen *n'* may be easily disconnected from rod *e'*, when but one of drivers *n* is to be used, by turning the pivoted cap *n''*, which retains the pitman on the rod, and thus allowing the end of the pitman to fall from the rod. Slotted stops *o o'* are adjustable in grooves *e'' o''* in frame *f*, for the purpose of retaining in proper position a cigar-box or other article to be nailed, which is to be held in contact with the end of trough *c*.

In operating the machine, the nails, which are placed promiscuously in inclined hopper *h*, attached to conductor *b*, slide down into the conductor, where they adjust themselves vertically in a row by their points falling through the slotted bottom of the conductor, leaving the nails hanging by their heads. In this position they slide down conductor *b* to carrier *a*. By pressing down with the foot on treadle *t* the movement of levers *b' b' b'* slides forward driver *n*, and when lug *i* on the driver comes in contact with collar *m* it moves forward rod *d* and turns carrier *a* a quarter of a circle, thus bringing slot *a'* in the carrier to an upright position, where it receives a nail from conductor *b*. Collar *m* is adjusted to such a position on rod *d* that when carrier *a* has been thus turned the forward end of driver *n* will have advanced to the end of trough *c* and driven a nail. By releasing the pressure on treadle *t* the reaction of spring *a'* reverses the movement of levers *b' b' b'* and draws back driver *n* until its lug *i* is in contact with nut *n'*, and then both driver *n* and rod *d* move back until carrier *a* is turned back and spring *e* 100

pressed out by the side of trough *c*, to allow the nail in slot *a'*, which is then in a horizontal position, to fall in trough *c* in front of driver *n*, with its head toward the driver. By again 5 pressing down treadle *t* the driver *n* moves forward and forces the nail into the box or other article that is held in contact with the end of trough *c* by stops *o o'*. As the nail will be inclined in the trough by reason of its point 10 being the lowest, to avoid the necessity of constructing with the same inclination the part of frame *f* on which the box to be nailed rests, I attach a slight spring, *s*, to the bottom of trough *c*, at or near its end, to project upward 15 into the trough and raise the point of the nail, in order that the nail may be level while being driven. The head of the nail while passing over spring *s* forces it down. The under side of trough *c* is cut away to receive spring 20 *s*, and the top of that part of the spring which projects into trough *c* is of a similar form to the bottom of the trough, in order to guide the point of the nail in a direct line. The two sides or sections of conductor *b*, forming the 25 slot between them in which the nails hang by their heads, may be farther separated, to enlarge the slot for larger nails, by means of the end piece, *s'*, which attaches them together at their outer ends, being slotted for the purpose 30 of adjustment.

I claim as my invention—

1. In a nailing-machine, the oscillating carrier *a*, having a horizontal or nearly horizontal axis and a slot, *a'*, provided with spring 35 *e*, and formed, as shown, of sufficient dimensions to receive but one nail hanging by its head on the circumference of the carrier, in combination with trough *c*, substantially as described.
- 40 2. The inclined slotted conductor *b*, in combination with carrier *a*, arranged to oscillate in a vertical or nearly vertical plane, and pivoted to the conductor, the carrier being actuated by a suitable mechanism, and having slot *a'*, provided with spring *e*, and formed as shown, substantially as described.
- 45 3. The driver *n* and trough *c*, in combination, by suitable means, with rod *d* and carrier *a*, having slot *a'*, provided with spring *e*, and formed as shown, and suitable actuating 50 mechanism, substantially as described.

4. The rod *d*, provided with collar *m* and nut *n'*, in combination with driver *n*, carrier *a*, having slot *a'*, provided with spring *e*, and formed as shown, trough *c*, and suitable actuating mechanism, substantially as described. 55

5. The driver *n*, trough *c*, rod *d*, and carrier *a*, having slot *a'*, provided with spring *e*, and formed as shown, in combination, as shown, with pitman *n''*, levers *b' b'' b'''*, spring *a''*, and treadle *t*, substantially as described. 60

6. Carrier *a*, having slot *a'*, provided with spring *e*, and formed as shown, in combination with rod *d*, nut *n'*, collar *m*, driver *n*, formed with lug *i*, rod *e'*, and pitman *n''*, provided 65 with the pivoted cap *n'''*, substantially as described.

7. The oscillating carrier *a*, having slot *a'*, provided with spring *e*, and formed as shown, in combination with conductor *b*, driver *n*, trough *c*, and suitable actuating mechanism, 70 substantially as described.

8. The frame *f*, formed with grooves *e'' o''*, in combination with the slotted adjustable stops *o o'*, trough *c*, carrier *a*, having slot *a'*, 75 provided with spring *e*, and formed as shown, driver *n*, and suitable actuating mechanism, substantially as described.

9. The adjustable trough *c*, formed to fit the transverse groove *g* in frame *f*, and with 80 slotted lug *c'*, in combination with conductor *b* and carrier *a*, having slot *a'*, provided with spring *e*, and formed as shown, substantially as described.

10. The trough *c*, provided with spring *s*, in 85 combination with driver *n* and suitable actuating mechanism, substantially as described.

11. The oscillating carrier *a*, having slot *a'* formed as shown, and provided with spring *e* and actuating mechanism, the carrier being 90 pivoted to conductor *b*, the driver *n*, pitman *n''*, and trough *c*, in combination with a similar carrier, driver, pitman, and trough, rod *e'*, lever *b'*, and suitable actuating mechanism, substantially as described.

EDWARD F. BARTON.
